UNITED STATES PATENT OFFICE.

PETER K. WILLIAMS, OF COLUMBUS, OHIO.

BELT BUCKLE.

Application filed September 13, 1922. Serial No. 588,067.

To all whom it may concern:

Be it known that I, PETER K. WILLIAMS, a citizen of the United States of America, residing at Columbus, in the county of

5 Franklin and State of Ohio, have invented certain new and useful Improvements in Belt Buckles, of which the following is a specification.

My present invention relates generally to 10 wearing apparel, and more particularly to waist line belts, my object being the provision of an adjustable arrangement which when once adjusted is of a permanently fitting character and needs but a simple 15 clasping and unclasping operation when fixing the same in and releasing the same from active position, which presents a neat balanced appearance at and upon opposite sides of the buckle, and which though unyielding at its buckle 20 connections, is provided with means permitting the same to give to natural or other body movements as required.

Another object is the provision of a belt 25 having a buckle provided with trouser engaging means so disposed and constructed as to act without undue strain with the object in view of holding the buckle centered on the trousers and against displacement in 30 either vertical or lateral directions.

With these and other objects in mind my invention proposes a belt of the character and construction, and for the purposes, illustrated in the accompanying drawing, 35 which forms a part of this specification, and wherein,

Figures 1 and 2 are front elevations of the opposite ends of the belt, Figure 1 showing the buckle engaging or clasping end 40 and Figure 2 showing the buckle carrying end.

Figures 3 and 4 are top plan views respectively of those portions of the belt shown in Figures 1 and 2,

45 Figure 5 is a top plan view of the buckle and the opposite ends of the belt engaged therewith in the active position,

Figure 6 is a front elevation of the parts shown in Figure 5,

50 Figure 7 is an enlarged longitudinal section through the adjustable loop forming die, taken substantially on line 7-7 of Figure 1,

55 Figures 8 and 9 are vertical sections through the buckle, illustrating the trousers engaging clamp thereof, Figure 9 being

taken centrally of the buckle substantially on line 9-9 of Figure 2, and

Figure 10 is a top plan view of the complete belt.

Referring now to these figures the belt proposed by my invention and generally indicated at 10 in Figure 10, is preferably provided with elastic inserts indicated at 11, at its opposite sides, in view of which it may although inelastic and unyielding at its buckle connections, give to natural or other body movements in case it becomes necessary to do so.

At one end the belt is formed with a permanent loop 12 by folding its extremity inwardly thereon and stitching the same as indicated at 13, this loop being either engaged directly with one of the upright rearwardly outstanding side bars 14 of the buckle 15, or engaged with a link 16 the latter in turn engaged with the bar 14.

The two upright side bars 14 of the buckle 15 which is thus permanently connected to one end of the belt 10, project rearwardly of and are rigid with the buckle at substantially spaced points upon opposite sides of the center of the latter so as to leave ample room as will be clearly seen by reference to Figures 2, 4 and 5 for a pair of lengthwise spaced rearwardly outstanding ears 17 between and to which a clamping lever 18 is pivoted. This lever has a depending clamping arm 19 whose inner or forward face is toothed or otherwise roughened so as to effectively clamp the inner surface of trousers indicated at A in Figures 8 and 9 over whose upper edge the lever is extended in the manner shown. This lever

90 has at its upper end an angular lip 20 projecting toward the buckle 15 and engaged by a spring 21 carried by the rear face of the buckle so as to hold the lever against accidental displacement in both the active and inactive positions, preventing movement 95 thereof unless the lever is actually pressed open or closed.

The other rear engaging bar 14 of the buckle 15 is adapted for engagement by a clasp 22 having a guard spring 23, this 100 clasp 22 having a belt receiving slot through which the normally free end of the belt is looped, with its extremity inturned as shown in Figs. 3, 5 and 7. This end loop indicated at 24 is for adjustment purposes and in its 105 adjustment cooperates with an adjusting slide 25 having spaced side bars 26 and a

rearwardly offset central bar 27 between which the belt is received so that by passing the extremity of the inturned portion of the loop 24 inwardly around the central upright bar 27 in the manner particularly shown in Figures 3 and 7, the parts will be frictionally engaged and held against displacement and in such manner that adjustment may be easily and quickly made when it becomes 10 desirable or necessary to do so.

It is obvious that the two ends of the belt engage the buckle in use in what is to all appearances the same manner, giving the belt a uniformly balanced appearance at and 15 upon opposite sides of the buckle which the usual belt with its exposed terminal, entirely lacks. Not only are the ends of the belt concealed, but the buckle connections are likewise concealed, and it is obvious that by 20 virtue of the disposition of these buckle connections upon opposite sides of the center of the buckle and upon opposite sides of a centrally disposed trouser engaging clamp, the latter is left entirely free and without 25 undesirable strain, to perform its intended functions and hold the buckle in connection

with the front of trousers substantially immovable while in place either in a vertical or in horizontal directions.

In the respects mentioned my invention 30 is therefore a decided improvement over the ordinary belt constructions now in general use, without undue complications and without adding to any material extent to the cost thereof.

35

I claim:

A belt buckle provided with spaced belt engaging connections upon its rear face and having rearwardly projecting ears between said belt connections, a vertically disposed 40 lever pivoted at its upper end between and to said ears and having a depending trouser engaging extension and a forwardly projecting lip at its upper end, and a spring secured vertically along the rear surface of 45 the buckle and having an upper free end engaging said lip to hold the lever in its active and inactive positions.

In testimony whereof I have affixed my signature.

PETER K. WILLIAMS.
